UNITED STATES PATENT OFFICE.

ALBERT F. MOHR, OF MILWAUKEE, WISCONSIN, ASSIGNOR TO INTERNATIONAL HARVESTER CORPORATION, A CORPORATION OF NEW JERSEY.

CARBURETER.

1,226,356.

Specification of Letters Patent. Patented May 15, 1917.

Application filed June 30, 1913. Serial No. 776,535.

To all whom it may concern:

Be it known that I, ALBERT F. MOHR, a citizen of the United States, residing at Milwaukee, in the county of Milwaukee and 5 State of Wisconsin, have invented certain new and useful Improvements in Carbureters for Internal-Combustion Engines, of which the following is a full, clear, and exact specification.

10 This invention relates to carbureters for internal combustion engines.

The object of this invention is to render it possible to operate internal combustion engines at high efficiency on fuel of both a 15 high and low grade under all and varying conditions.

This object is accomplished by providing a carbureter having a mixing chamber, fuel supply means associated therewith, and 20 means for supplying hot and relatively cold air to said mixing chamber in which liquid fuel and air, and under certain conditions water, are mixed preparatory to passing into the combustion chamber or chambers of an internal combustion engine, the supply of water and hot and cold air being controlled in a manner to meet the requirements of all conditions.

The invention is illustrated on the accompanying sheets of drawings, in which Figure 1 is a front elevation of my carbureter shown as connected to the cylinders of a twin cylinder engine;

Fig. 2 is a side elevation of the same carbureter;

Fig. 3 is a vertical sectional view of a portion of the carbureter taken along the plane of line 3—3 of Fig. 2, showing a secondary air supply conduit with a spring 40 pressed air and water control valve therein;

Fig. 4 is a vertical sectional view of the fuel containing receptacle connected to the body portion of the carbureter, the section being taken along the plane of line 4—4 of 45 Fig. 1; and,

Fig. 5 is a transverse sectional view of the same fuel receptacle taken along the irregular line 5—5 of Fig. 4.

The various novel features of my invention will be apparent from the description and drawings, and will be particularly pointed out in the appended claims.

Connected to the cylinders 10 of a twin cylinder internal combustion engine is my carbureter 11, including a hollow base portion 12 upon which is mounted a mixing

chamber 13 to which is secured a fuel or oil containing receptacle 14 divided into two parts or chambers 15 and 16 by a partition 17. The part 15 is supplied with gasolene 60 through an inlet pipe 18, the gasolene being maintained at a constant level by means of a wall 19, the excess gasolene flowing out through an overflow pipe 20. The other part 16 is supplied with a heavier grade of 65 fuel oil, such for example as kerosene, distillate, or solar oil, said lower grade of fuel oil being supplied through inlet pipe 21, being maintained at a constant level by means of a wall 22, and the excess passing out 70 through an overflow pipe 23. This oil containing receptacle 14 is provided with a conical channel 24 in which is located a conical plug 25 having an L-shaped passageway 75 26, one end of which at all times communicates with a vertical oil passageway 27, which in turn communicates with the passageway in a nozzle 28, the nozzle being provided with a hand controlled needle valve 29 for controlling the supply of liquid fuel. The other end of the L-shaped passageway 26 in plug 25 is adapted to communicate 80 with either the gasolene containing chamber or the other chamber containing the heavier or lower grade of fuel. This plug 85 is provided with a handle 30 by means of which the plug may be turned to two extreme positions whereby oil may be supplied from either of the oil chambers 15 or 16, or the plug may be turned into a neutral position preventing the flow of oil from either chamber into said plug. Connected to the oil containing receptacle and located within the opening 31 in the mixing chamber 13 is an annular member 32 in which there is a diagonally arranged opening 33 into which the nozzle 28 projects, the opening 33 directing in-rushing air past said nozzle in a manner to draw oil therefrom. The fuel containing receptacle 14 is provided with an opening 34, in which is secured one end of a primary hot air supply pipe 35, the other end of which is connected to a pipe or conduit 36 which communicates with a source of air heated by the exhaust pipe (not shown) of the engine cylinders 10. This pipe 36 is provided with a butterfly valve 37 manually controlled by a handle 38 connected with said valve, the valve being held in any adjusted position by a detent engaging a notched member 39. The butterfly valve is located adjacent the

point at which the pipes 35 and 36 join and controls the passage of air into the pipe 35 and also a secondary or auxiliary pipe 41.

This secondary or auxiliary air supply pipe is connected to the conduit 13 through a member 40. The member 40 is provided with an annular valve seat 42 having an opening 43 through which water may be supplied from a water pipe 44, the flow of water being controlled by a hand operated needle valve 45. A puppet valve 46 is held in closed position against the valve seat 42, thus normally preventing a supply of air through the conduit 41, and also preventing a supply of water through the opening 43, the port of which is covered by the valve 46. This valve, which is controlled by the suction of the engine, is held in closed position by a spring 47 surrounding the valve stem 48, the tension of which spring being adjustable by a hand screw 49. Located in the pipe 41 is a butterfly valve 50 which is adapted to be adjusted by a handle 51 having a detent 52 for engaging notches in a notched plate 53 for holding said butterfly valve in any adjusted position. This butterfly valve is to control the supply of relatively cold air. Located in the mixing chamber 13 is a throttling valve 55 automatically controlled by an engine governor (not shown) connection to which is made by a rod 56.

When an engine is operated in a hot climate, the air is usually sufficiently warm to vaporize the oil, especially the lighter oils, so that when the mixture enters the combustion chamber it can be ignited and thereupon expanded for doing work efficiently. Under such conditions it is unnecessary to supply hot air from around the exhaust pipe of an engine to meet the operating requirements. In the cold climates, the cold air without first being heated would not be satisfactory. For this reason it is necessary to introduce hot air into the carburetor to vaporize the oil preparatory to passing into the combustion chamber. After the engine is thoroughly heated, it may be advantageous to shut off a limited supply of hot air and permit a limited supply of cold air. In a temperate climate engines are operated under varying conditions. It may be cold one day and hot the next, or even cold and hot on the same day. If a heavy fuel oil is used under these conditions, it may be used satisfactorily while the weather conditions are warm, but unsatisfactorily when cold. For these reasons, among others, I have provided my carburetor with the main hot air inlet pipe 35 which is connected through pipe 36 to a source of hot air, and also with an auxiliary cold air supply pipe 41, the pipe 36 having the hand-controlled butterfly valve for controlling the supply of heated air, and the cold air supply pipe having the

hand controlled butterfly valve 50 for controlling the supply of cold air. When starting an engine, due to the fact that the cylinder walls are cold, it is usually necessary to use a relatively high grade of oil, such as gasolene. This is also true due to the fact that compression is low on no and light load and a comparatively rich mixture is needed. For starting, therefore, the handle 30 is adjusted so that the L-shaped passageway 26 of the plug 25 communicates with the gasolene chamber 15, the gasolene passing up the vertical passageway 27 and through the nozzle 28, the oil being drawn from the nozzle 28 by inrushing air passing through the pipes 36 and 35, the butterfly valve 37 being partially open at this time, and the valve 50 closed. This inrushing air, caused by the suction of the engine, takes a path completely surrounding the nozzle, the path being formed by the member 32. As soon as the engine becomes heated, the plug 25 may be swung through an angle of 180°, thereby cutting off the supply of gasolene, and causing the L-shaped passageway 26 of the plug 25 to communicate with the receptacle containing the relatively heavy oil whereby such heavy oil passes through the passageway 27 and nozzle 28 under the influence of the inrushing air past said nozzle. In using the relatively heavy fuel oils, it is necessary to use air heated a certain amount to vaporize the fuel sufficiently so that the engine may operate efficiently. For this reason, the butterfly valve 37 is usually held partially open, permitting a flow of hot air from pipe 36 to pipe 35, and at the same time practically preventing, especially under no and light load conditions, a supply of hot air from the pipe 36 to the pipe 41 to which it is connected. It is seen that if the butterfly valve 37 be swung into full open position, hot air would be supplied to both the pipes 35 and 41, but under no load and light load conditions, the hot air supplied to pipe 41 would not pass into the mixing chamber 13 for the reason that the valve 46 is held in its closed position by the spring 47. When the load on the engine is increased to a certain predetermined point, the throttling valve 55 gradually opening more and more, the suction created by the engine will be sufficient to open the valve 46 slightly to permit the supply of air through the pipe 41, and at the same time permit water to be drawn through the opening 43. Water up to this point is not permitted to form a part of the mixture for the reason that it would be detrimental in that it would recondense part of the fuel oil and cool the cylinder walls of the engine. However, after the load on the engine has increased above this predetermined amount, water is a necessary element in the mixture to prevent, not only heating of the engine, but also to

prevent pre-ignition and a too rapid flame propagation, which is the cause of knocking in the cylinders. As the load on the engine continues to increase, the throttling valve 55 continuing to open more, a relatively greater amount of air and water is drawn in through the pipes 35 and 41 into the mixing chamber 13 which leads directly to the cylinders. Under light load conditions, a relatively rich mixture is necessary for the reason that the compression is low, but under heavy load conditions, a relatively greater amount of air may be supplied because the compression is high. This is controlled by the automatically actuated governor controlled throttle valve 55.

With the butterfly valve 50 open, cold air will flow past butterfly valve 37 through pipe 35, past nozzle 28, this being especially true with the valve 37 properly adjusted with the engine working on no or light loads. It is seen, therefore, that with valve 50 open, more or less cold air can be supplied through pipe 35, depending upon the position of valve 37. With the engine working on heavy loads and the valve 37 open, it is apparent that more or less hot air can be supplied to the mixing chamber 13 through pipe 41. The pipe 35, however, is the primary air supply pipe which furnishes hot air normally, and pipe 41 is the secondary air supply pipe and furnishes cold air normally, water also being furnished through pipe 41 when the engine is working on relatively heavy loads.

Any conditions may be met by adjusting properly the positions of the butterfly valves 37 and 50.

It is evident that there may be various modifications in the arrangement herein particularly shown and described, and it is my intention to cover all such modifications which do not involve a departure from the spirit and scope of my invention as set forth in the appended claims.

45 What I claim as new is:

1. In a carbureter for internal combustion engines, the combination of a mixing chamber, a hot air connection thereto, fuel supply means in said hot air connection directed into said mixing chamber, a connection which is normally open and through which cold air is normally supplied to said mixing chamber, a valve in said hot air connection to control the passage of air therethrough, and control means for said cold air supply, said hot and cold air connections being connected at a point independent of the mixing chamber.

2. In a carbureter for internal combustion engines, the combination of a mixing chamber, fuel supply means directed thereinto, a primary air connection to said chamber, a secondary air connection to said chamber,

said connections being connected at a point independent of the mixing chamber, and single means for controlling the supply of air through one or both of said connections.

3. In a carbureter for internal combustion engines, the combination of a mixing chamber, fuel supply means associated therewith, a hot air connection to said mixing chamber, a cold air connection to said chamber, and means in said hot air connection controlling the supply of hot air through both of said connections to said chamber.

4. In a carbureter for internal combustion engines, the combination of a mixing chamber, fuel supply means associated therewith, a hot air connection to said chamber, a cold air connection to said chamber, and means in said hot air connection controlling the supply of hot air therethrough and also the supply of cold air through said hot air connection to said chamber.

5. In a carbureter for internal combustion engines, the combination of a mixing chamber, fuel supply means associated therewith, two air connections entering the mixing chamber separately, and means in one of said connections controlling the supply of air through both of said connections to said chamber.

6. In a carbureter for internal combustion engines, the combination of a mixing chamber, fuel supply means associated therewith, a hot air connection to said mixing chamber, a cold air connection to said mixing chamber, and means in one of said air connections for controlling the supply of hot air through both of said connections to said chamber.

7. In a carbureter for internal combustion engines, the combination of a mixing chamber, fuel supply means associated therewith, controlled communicating hot and cold air supply connections leading separately to said mixing chamber, and water supply means associated with one of said connections.

8. In a carbureter for internal combustion engines, the combination of a mixing chamber, fuel supply means connected thereto, a primary air supply connection to said chamber, a valve for controlling the supply of air therethrough, a secondary air connection to said chamber, a valve for controlling the supply of air therethrough, said primary and secondary air connections being connected at a point independent of the mixing chamber, a suction controlled valve in one of said connections, and a governor controlled throttling valve in said mixing chamber.

In testimony whereof I affix my signature, in the presence of two witnesses.

ALBERT F. MOHR.
